(57) **CLAIM**

We claim the ornamental design for a cleaning roller brush for footwear care machine, as shown and described.

DESCRIPTION

FIG. 1 is a perspective view of a cleaning roller brush for footwear care machine showing a new design;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view of the cleaning roller brush for footwear care machine showing a brush disassembled from the article; and,

FIG. 9 is a perspective view of the cleaning roller brush for footwear care machine showing the location when in use. The dot-dash broken lines shown in FIGS. 8-9 is for the purpose of illustrating the link of the detail partial view as part of another view and form no part of the claimed design. The broken lines showing of a footwear care machine in FIG. 9 are for the purpose of illustrating environmental structure and form no part of the claimed design. All other

(Continued)

broken lines represent portions of the cleaning roller brush for footwear care machine that form no part of the claimed design.
